UNITED STATES PATENT OFFICE

JOHANN HÜSER, OF POLSUM, GERMANY

GRINDING MACHINE

Application filed February 15, 1929, Serial No. 340,094, and in Germany March 19, 1928.

My invention relates to improvements in grinding machines, and more particularly in grinding machines for grinding wooden articles such as handles of spades and the like, 5 and comprising a travelling band carrying a grinding powder such as sand for grinding the articles pressed thereon, the said band co-operating with rollers disposed above the same and angularly thereof and controlling 10 the feeding of the blanks. The object of the improvements is to provide a grinding machine of this type in which the said rollers are mounted so that they adapt themselves to blanks of different dimensions, and with this 15 object in view my invention consists in rockingly mounting the frame carrying the rollers on a rockable lever adapted to move the said frame towards and away from the band.

For the purpose of explaining the invention an example embodying the same has been shown in the accompanying drawings in which the same letters of reference have been used in all the views to indicate corresponding parts. In said drawings,

25 Fig. 1 is an elevation showing the grinding machine,

Fig. 2 is an elevation of the machine looking from the left in Fig. 1,

Fig. 3 is a sectional plan view taken on the 30 line 3—3 of Fig. 1,

Fig. 4 is an elevation partly in section and on an enlarged scale and showing the feed rollers and the frame and operating mechanism thereof, and

35 Fig. 5 is a top plan view of Fig. 4.

In the example shown in the figures the grinding machine comprises a table 5 provided with uprights 6. At the left hand end of the table a driving shaft 7 is mounted in 40 bearings 8, which driving shaft is provided with pulleys 9 connected with a power shaft. At the side of the table 5 opposite to the shaft 7 an idle shaft 10 is mounted in bearings 11, and to the shafts 7 and 10 drums 6 are mounted on which an endless tape or band *a* is trained. On one of the uprights 6 a shaft *f* is mounted in bearings 12, and on the said shaft a lever *g* is rockingly mounted, the said 45 lever carrying at one end a frame *d* and at its opposite end a weighted body *h*. On the

frame *d* feed rollers *c* are mounted, and the frame is rockingly suspended from the lever *g* by means of a joint *u* (Figs. 4 and 5).

The construction of the feed rollers *c* and the frame carrying the same is shown in detail in Figs. 4 and 5. As shown in the said figures, the frame comprises a U-shaped bail 13 and transverse bars *d* and *d'* fixed to the bottom ends of the flanges of the bail and provided with eyes 14 providing bearings for 55 the trunnions 30 of the rollers *c*. As is best shown in Fig. 5, the member *d'* is offset at one end for accommodating mechanism for driving the rollers *c*, and the said offset end is made integral with an 60 upwardly directed arm 15 fixed at its top end to the web portion of the bail 13. The rollers *c* are provided with circumferential grooves on which a rope *p* is trained, so that the said rollers are rotated in unison. The 65 shaft of one of the rollers *c* extends outwardly through its bearing 14, and it carries a bevel gear *o* in mesh with a similar bevel gear *o'* keyed to a shaft *r*, the said shaft being mounted in a bearing block 16 secured to the 70 arm 15. At its top end the shaft *r* carries a bevel gear *n* which is in mesh with a similar bevel gear *n'* secured to a shaft 17, the shaft 75 17 is rotatably mounted in a block 18 secured to the bail 13, and it carries a pulley 19. The shaft 17 is passed through an eye *u* of the lever *g*.

The pulley 19 is connected by a belt *m* with a pulley 20 secured to the shaft *f*, and the shaft *f* is adapted to be rotated by means of 80 a pulley 21 secured thereto, a belt *k* and a pulley 22 from a shaft 23 mounted in bearings 24 and connected with the shaft 7 by pulleys 25 and 26 and a belt 27.

The block 18 is secured to the bail 13 by 85 means of wing nuts *t* passed through slots *s* of the bail and permitting the frame *d* and the rollers *c* to be fixed in different angular positions relatively to the band *a*.

The operation of the grinding machine is as 90 follows:

The frame *d* is fixed to the block 18 with the rollers *c* in the desired angular position relatively to the band *a*. The band *a* receives 95 a supply of grinding material such as sand,

and the machine is connected to the power shaft. Thereby the band *a* is made to travel in the direction of the arrow *x* shown in Fig. 3, and the rollers *c* are rotated by means of the belt 27, the shaft 23, the belt *k*, the shaft *f*, the belt *m*, the shaft 17, the bevel gears *n*, *n*¹, the shaft *r*, the bevel gears *o*, *o*¹, and the rope *p*. The rollers *c* are pressed on the blank held on the band *a* by means of a rod 28 jointed to the lever *g* and connected with a foot lever *i*. By reason of the rocking suspension of the frame *d* from the lever *g* the rollers *d* are able to set themselves in the proper way on blanks of different thickness. 15 The blank is rotated by the rollers *c* and the band *a*, and they are simultaneously shifted transversely of the band *a* by reason of the inclined position of the rollers *c*.

For varying the lateral movement of the 20 blank the angular position of the rollers *c* relatively to the band *a* is varied by fixing the block 18 in different angular positions on the bail 13.

While in describing the invention reference 25 has been made to a particular example embodying the same I wish it to be understood that my invention is not limited to the construction shown in the drawings, and that various changes may be made in the general 30 arrangement of the apparatus and the construction of its parts without departing from the invention.

I claim:

1. A grinding machine of the character set 35 forth, comprising an abrading belt, a lever and a frame, the lever being swingably mounted on a shaft and the frame depending from the lever above said belt, rollers carried by the frame to operate upon a workpiece 40 upon said belt, and manually operated means for forcibly drawing the lever downwardly at will to cause the rollers to exert an application of force upon the workpiece.

2. A grinding machine of the character set 45 forth, comprising an abrading belt, a shaft, a lever thereon, said lever being mounted intermediate its ends for rocking movement and carrying a weight to one side of said shaft, a frame on the opposite side of the lever, depending therefrom over said belt, rollers on the frame, adapted to operate upon a workpiece upon said belt, and a treadle operated rod attached to said lever on the same side thereof from which the frame depends, for forcibly drawing the lever downwardly to cause the rollers to exert an application of force upon the workpiece.

3. In a grinding machine of the character 50 set forth, the combination with a driven abrading belt and a driven shaft, of a lever mounted on the shaft for rocking movement, a frame depending from the lever to rock therewith and arranged over said belt, rollers 55 on the frame adapted to operate upon a work-

piece upon the belt, and means for rotating the rollers from said shaft.

4. In a grinding machine of the character set forth, the combination with a driven abrading belt and a driven shaft, of a lever 70 mounted on the shaft for rocking movement, a frame depending from the lever to rock therewith and arranged over said belt, rollers on the frame adapted to operate upon a workpiece upon the belt, means for rotating the rollers from said shaft, and manually operated means for forcibly drawing the lever downwardly to cause the rollers to exert an application of force upon the workpiece during the rotation of the rollers.

5. A machine of the character set forth, having in combination, a pair of shafts carrying drums, one of the shafts constituting a driving shaft, an abrading belt connecting the drums, a countershaft and means for operating it from one of the drum shafts, a lever mounted on the countershaft for rocking movement, a frame depending from the lever over said belt, rollers on the frame adapted to operate upon a workpiece upon said belt, and means for operating the rollers from said countershaft.

6. In a machine of the character set forth, the combination with a shaft, of a lever mounted on the shaft for rocking movement, a frame carried by the lever, rollers on the frame, means by which to impart rocking movement to the lever, and means for driving the rollers from said shaft.

7. In a machine of the character set forth, the combination with a shaft, of a lever mounted on the shaft for rocking movement and carrying a frame at a point distant from the shaft, a pair of rollers on the frame, means for driving one of the rollers from said shaft, and a driving connection between said rollers.

In testimony whereof I hereunto affix my signature.

JOHANN HÜSER.
